ERNEST H. THOMPSON, OF CHICAGO, ILLINOIS, ASSIGNOR TO JOHNSON FARE BOX CO.,
A CORPORATION OF NEW YORK.

COIN-DISPENSING APPARATUS.

1,404,909.

Specification of Letters Patent. Patented Jan. 31, 1922.

Application filed June 21, 1918, Serial No. 241,122. Renewed June 27, 1921. Serial No. 480,910.

To all whom it may concern:

Be it known that I, ERNEST H. THOMPSON, a citizen of the United States, and a resident of the city of Chicago and State of Illinois, 5 have invented certain new and useful Improvements in Coin-Dispensing Apparatus, of which the following is a specification.

The invention relates to coin dispensing apparatus such as may be conveniently set 10 up in places where change is required and which may be attached to the belt or garments of conductors. The nature of the improvements will appear from the specification.

15 An example of the improved coin dispensing apparatus is illustrated in the drawings, in which Fig. 1 is a front elevation of the apparatus; Fig. 2 is a vertical section on line 2—2 of Fig. 1; Fig. 3 is a horizontal section on line 3—3 of Fig. 1; Fig. 4 is an enlarged detailed sectional view similar to the lower part of Fig. 2; Fig. 5 is a diagrammatic perspective view showing the relation between four of the slides; Fig. 6 is 20 an inverted plan view; Fig. 7 is a bottom view with the bottom plate and the actuating mechanism of Fig. 6 removed; and Figs. 8 and 9 are views similar to Fig. 7 but showing the slides in different relations.

30 The device as illustrated comprises three coin containers *a*, *b* and *c*, constructed preferably in the form of cylinders and adapted to contain respectively a supply of quarters, nickels and dimes. These cylinders, *a*, *b* and 35 *c* are filled by inserting the coins through slots *d* suitably located at the upper portion thereof, the upper part of the cylinders being otherwise closed to prevent the withdrawal or ejection of the coins at this 40 point; apertures *e* may be provided in the cylinders to indicate when the supply of coins in the reservoirs becomes low. The cylinders *a*, *b* and *c*, are carried by a plate *f* and may be connected therewith in any 45 suitable manner as for instance by having their lower ends soldered to or otherwise formed as an integral part of said plate *f*, the latter being formed with openings corresponding to and registering with the lower 50 open ends of said cylinders as shown in Figs. 2 and 4. The plate *f* is so shaped as to provide guideways for the coin ejecting slides, which, in the drawings, are designated as *g*, *h*, *i*, *j* and *k*, and are provided with suit-

able ejector orifices or recesses adapted, in 55 the normal positions of the slides, to register with the cylinders *a*, *b* and *c*, and more fully referred to hereinafter, said slides being held in place from below by a plate *l*, preferably detachably secured in position 60 by means of screws or the like *l'*. In the illustrated example the plate *f* is secured to a carrying plate *p* which thus serves as a support for the cylinders, *a*, *b* and *c*, a bracket *p'* being located between the plate 65 *p* and the cylinders at a distance from the plate *f* to increase the rigidity of the cylinders with respect to said plate *p*; the latter, as shown, may be formed with slots *p*² for the accommodation of a belt or the like 70 whereby the apparatus may be secured in proper operative position upon the person of a conductor or other individual receiving money or making change. The plate *l* is provided with semi-circular recesses *m*, at 75 the forward edge thereof, each recess corresponding with the rear inner edge of the coin ejecting recess or orifice of the cooperating slide, said plate *l* being also provided with a downwardly extending flange *n*. Pins 80 or rods *o* each have one end secured to said flange *n* and the other end secured to the plate *p* so that said pins or rods *o* extend between the flange *n* and plate *p* in parallel and spaced relation for the purpose to be 85 more fully explained further on in the description. The slide *g*, used as the ejector for the reservoir containing quarters, has an ejector orifice or recess corresponding in the size and shape to a quarter and normally 90 registering with the cylinder *a* so that one quarter will at all times lie within the said slide. In the normal position of the apparatus, the bottom plate *l* will prevent the coins from falling through. The slide *g* at the 95 rear thereof, terminates in a finger piece *r* which projects through a suitable opening *l*² in the plate *l* and is guided on one of the pins *o* which extends therethrough for this purpose as shown in Fig. 2. The springs *q* 100 which surround each of said pins *o* are compressible between the finger piece *r* and the flange *n* of the plate *l* and serve to maintain and return said slide *g* in and to its position of rest. When, therefore, the finger piece 105 *r* and with it the slide *g* is drawn forward, the quarter which is contained in the slide will be moved forwardly until the rear edge

2
of the ejector orifice or recess of the slide coincides with the corresponding recess *m* of the plate *l*, whereupon the coin is released and falls from the ejector slide while the 5 balance of the coins in the reservoir are prevented from falling out because the rear part of the slide and the plate *l* are in the way. The cooperating spring *g* then returns the slide to its normal position, whereupon the 10 column of quarters descends to the extent of the thickness of one coin, the bottom coin being then again located within the recess of the ejector slide.

The general operation of the remaining 15 slides and ejectors is substantially similar to that described with respect to the ejector for the column containing quarters. The arrangement of the remaining slides, however, is such that by the use of selective 20 finger pieces change can be made either for one dime or for a quarter, and in the latter case the change may consist either of two dimes and a nickel or of five nickels. This is accomplished by providing the reservoir 25 *b*, adapted to contain nickels, with three superposed slides, the top one *h* accommodating three nickels while each of the lower slides *i* and *j* accommodate but one nickel. The slide *k* for the dimes is adapted to contain 30 two coins.

The action of these four slides is clearly illustrated in Fig. 5. The operation is such that when the selective finger piece *s* is operated, it will draw forward the two lower slides *i* and *j* of the nickel container without causing any movement of the slide *h*. The two slides *i* and *j*, moving forward together, cause two nickels to be dropped at each operation, thus providing change for 35 a dime whenever desired. If five nickels are wanted in change for a quarter, the finger piece *t* is operated, which will cause the three slides *h*, *i* and *j* to move forward together, thus permitting the ejection of 40 five nickels at each operation. If, on the other hand, change consisting of two dimes and a nickel is desired, the finger piece *u* is drawn forward, which will cause movement of the dime slide *k* and the lowermost 45 nickel slide *j*, thus releasing two dimes and a nickel at once. A guide finger *v* is interposed in the path of the falling nickels so as to guide them into the hand of the operator, so that dimes and nickels will fall together in the same general direction instead 50 of descending as separate columns.

As before stated, the entire apparatus is fastened to a rear plate *p*, which extends below the bottom of the ejector slides where 55 it forms a smooth guiding plate for the fingers, leaving room approximating the thickness of the finger between the plate and the downwardly projecting parts of the finger pieces *r*, *s*, *t* and *u*, thereby assisting the fingers to find their proper places and

at the same time forming a smooth bearing against which the fingers may rest in exerting pressure on the finger pieces.

The particular mechanism by which the various slides are caused to act is best shown 70 in Fig. 5. From this figure it appears that the lowermost nickel slide *j* is not movable by itself but can only be moved in cooperation either with the middle nickel slide *i* or the dime slide *k*. It is, however, spring- 75 controlled as the result of the projection *w* abutting against one of the coil springs *q* in a manner similar to the abutment of such a spring against the finger pieces of the other slides. When the dime slide *k* moves 80 in the direction of the arrow, it will move with it the nickel slide *j* by reason of the abutment of the finger piece *u* with the projection *x* mounted on the nickel slide *j*. The remaining two nickel slides will be unaffected by this movement. If, on the other hand, it is desired to eject two nickels only, the selective finger piece *s* is moved in the direction of the arrow and abutting as it does against the slide *j*, draws this forward 90 without affecting either the nickel slide *h* or the dime slide *k*. If five nickels are desired, the finger piece *t* is moved forward and by its abutment with the slide *i* moves that slide forward, thus in turn also moving 95 forward the slide *j*, so that these three slides move forward together without causing movement in the dime slide *k*. It is apparent that this co-acting system of slides can be varied to bring about a number of 100 different combinations, but those shown are sufficient to make change for funds of all denominations with respect to which a five cent piece is to be present in the change.

The device, as illustrated, is adapted for 105 operation by the left hand because the finger piece *r* which controls the quarter reservoir will offer the least resistance to the fingers and is, therefore, placed in the path of the small finger. The slide *s*, which offers 110 greater resistance (two springs being required to be compressed) is arranged to be actuated by the ring finger. The slide *t*, which has three springs to compress, is operated by the middle finger, while the 115 slide *u* is operated by the index finger. The mechanism when adapted for operation by the right hand will be preferably reversed so that the quarter and dime columns change places, together with their respective operating 120 parts, and the finger pieces *t* and *s* are correspondingly transposed. If desired, the finger pieces *r*, *s*, *t* and *u* may be constructed so as to be readily distinguished, one from the other, by the sense of touch.

An important consideration in apparatus of this kind is that which flows from the fact that coins of one denomination are seldom of uniform thickness. New coins are thicker than old coins. In order 130

to make the operation of the device certain, the depth of the apertures in the ejector slides is such that it will accommodate coins of the maximum thickness.

- 5 Should coins of lesser thickness be contained in the column, as indicated by the dotted lines in Fig. 4, the mechanism would be clogged were it not for the fact that I have provided the rear portion of the ejector 10 slides with the beveled or inclined surfaces γ . The forward edge of this bevel is so located in each case that it will be lower than the top of the coin of the required denomination whether all the coins are thin or 15 all the coins are thick. This forward edge of the bevel is also located above the lower surface of the top coin whether of maximum thickness or of minimum thickness. The result of this arrangement is that no matter what the thickness of the coins may be, only the required number will be ejected, the coin next above, if it projects into the path of the moving slide, will be prevented from forward movement by the edges α of the reservoir above. As the slide moves forward the incline portions γ will elevate the column of coins in the reservoir and hold them in position until the slide is retracted and the entire column of coins comes down. It will be noted that the finger pieces r, s, t and u , in their normal positions, are located to the rear of a plane drawn through the major axes of the cylinders a, b , and c , or rearwardly of the coin ejector recesses, and are thus protected by the overhanging elements of the apparatus, such as the plate l against unintentional operation and also against contact with extraneous objects such as, for instance, the clothing of passers-by. Injury to 40 said clothing or to the apparatus, or to both, is thus prevented.

It is manifest that the apparatus de-

scribed is capable of numerous modifications within the scope of the invention and the claims hereto appended are intended to cover any such modifications or developments.

I claim:

1. In a coin dispensing apparatus, the combination of a plurality of coin receptacles adapted to contain coins of different denominations, ejector slides whereby coins are discharged from said receptacles, means whereby said slides are selectively operated either individually or in predetermined combination, and means whereby the operation of said slides is yieldingly resisted in varying degrees in accordance with the operative selection, the operative means being disposed in positions of ready accessibility to the fingers having muscular power best adapted to overcome said different degrees of resistance.

2. In a coin dispensing apparatus, the combination of a plurality of coin receptacles located adjacent to each other, a group of ejector slides located in superimposed relation at the discharge end of one receptacle, an individual ejector slide located at the discharge end of another receptacle and adjacent to said group of slides, finger pieces on certain of said group of slides arranged to engage others of said group of slides whereby the latter are selectively coupled together and actuated, a projection extending laterally from one of said groups of slides and a finger piece on said individual slide arranged to engage said projection whereby said last two mentioned slides are coupled together and coincidentally actuated independently of the other slides in said group.

In testimony whereof I have hereunto set my hand.

ERNEST H. THOMPSON.
